UNITED STATES PATENT OFFICE.

WILLIAM B. SMITH, OF NEW YORK, N. Y., ASSIGNOR TO THE SMITH ADJUSTABLE CAR-AXLE BEARING COMPANY, OF SAME PLACE.

DESIGN FOR A CROWN-BACK FOR CAR-AXLE BEARINGS.

SPECIFICATION forming part of Design No. 28,892, dated June 21, 1898.

Application filed May 25, 1898. Serial No. 681,751. Term of patent 14 years.

To all whom it may concern:

Be it known that I, WILLIAM B. SMITH, a citizen of the United States, and a resident of New York, in the county and State of New York, have invented and produced a new and original Design for a Crown-Back for Car-Axle Bearings, of which the following is a specification.

The leading features of my design consist in a crown-back for car-axle bearings, the top of which is rounded and having an elongated projection uprising from the crown of the rounded portion, the said elongated projection being tapered both in width and thickness.

In the accompanying drawings, Figure 1 represents the crown-back in perspective. Fig. 2 is a top plan view. Fig. 3 is a bottom plan view. Fig. 4 is a view in side elevation, and Fig. 5 is a view in end elevation.

A represents the crown-back as a whole, a' represents the convex or rounded top, and a'' represents the elongated projection uprising from the rounded or convex top a' . Ears a^3 project from the opposite sides of the crown-back.

What I claim is—

The design for a crown-back for car-axle bearings, substantially as shown and described.

In testimony that I claim the foregoing as my invention I have signed my name, in presence of two witnesses, this 13th day of May, 1898.

WILLIAM B. SMITH.
